UNITED STATES PATENT OFFICE.

CLARENCE H. DOCKHAM, OF DETROIT, MICHIGAN, ASSIGNOR TO CHICAGO PNEUMATIC TOOL COMPANY, OF DETROIT, MICHIGAN, A CORPORATION OF NEW JERSEY.

TOOL RETAINER.

Application filed February 22, 1921. Serial No. 448,377.

To all whom it may concern:

Be it known that I, CLARENCE H. DOCKHAM, a citizen of the United States, residing at Detroit, in the county of Wayne and State of Michigan, have invented certain new and useful Improvements in Tool Retainers, of which the following is a specification.

My invention relates to a retainer for retaining the working tool of impact tools such as the drill steel of a fluid pressure operated drill. The object of my invention is to produce a simple, efficient and reliable retainer of this character possessing advantages over retainers heretofore used. Moreover my retainer is provided with means for positively maintaining the retainer in its working position under all conditions. Furthermore such retainer is so made as to withstand the blow of the hammer through the working tool or drill steel when such steel is withdrawn from a bad hole. By holding the drill steel within reach of the piston a vibration is set up on the steel which will clear the same from the hole under any condition. Other novel and advantageous features of construction and operation will be apparent from the description hereinafter given.

In the drawing Fig. 1 is a plan view of the front end of a drill to which my invention is shown applied; Fig. 2 a side elevation thereof with a portion of the retainer in section; Fig. 3 an end view thereof; Fig. 4 an elevation of the lock collar alone; Fig. 5 a side elevation of the retainer proper; and Fig. 6 a front elevation of the inner ring or collar with the arms of the retainer in section on the line 6—6 of Fig. 2. For the sake of a clear and definite description of my invention I have shown the same applied to a rock drill and cooperating with the working tool thereof which is a drill steel, but it will be understood that my invention is not limited to this specific use.

Referring to the embodiment of my invention as herein shown the rock drill has the usual front head 1 in which is inserted the working tool or drill steel 2 against which the hammering piston (not shown) delivers its blow either directly or indirectly through the usual anvil piece. The retainer is mounted upon this front head and has a member which cooperates with the drill

steel and also with the usual enlargement or collar 3 thereon in the manner herein-after explained. A collar or ring 4 is mounted to slide longitudinally on the front head 1 against the tension of a coiled spring 5 encircling such head and interposed between the ring and a lock collar 6. The ring is normally held to its normal rearward position against the shoulder 7 on the head by this spring but is adapted to yieldingly move forward against the tension thereof. The ring has such a longitudinal movement but is prevented from rotating thereon by reason of the provision of complementary flats of such head 1 and in the ring 2. The lock collar, shown by itself in Fig. 4, is provided with a series of grooves 8 and recesses 9 which are adapted to cooperate with lugs 10 on the forward end of the front head 1 of the drill in such a manner that after the collar has been inserted on such front end and been turned angularly the proper distance the recesses 9 will engage with the lugs whereby the collar will be removably locked in position on such end of the head.

The retainer proper consists of a frame having opposite parallel side members 11—11 pivoted at their rearward or free ends upon the pins 12 on opposite sides of the ring 4 and a connecting cross piece or yoke portion 13 which straddles the drill steel 2 as shown in Fig. 3, the same being arranged in the path of movement of the collar 3 of such drill.

A holding ring 14 encircles the retainer and is adapted to be slid on the arms 11 which act in offset grooves or recesses 15 in the collar, as shown in Fig. 3. The retainer proper is normally in the working position shown in the drawing but the same is adapted to be swung upwardly. Obviously when the collar 14 is in its forward position as shown in the drawing the retainer is held in its working position in cooperation with the drill steel but when such collar is slid rearwardly to or back of the pivotal point of the retainer, such retainer may be freely swung upwardly out of range of the drill steel. The collar 14 is held in its normal forward position by suitable means such as the spring finger 16 secured to the lock collar 6 by the screw 17 and passing through a hole 18 in the collar 14 and also having a curved free end 19.

By moving the free end 19 inwardly the collar 14 may be withdrawn from the finger and be retracted rearwardly.

As shown in Fig. 4 the lock collar 6 is 5 preferably provided with opposite lugs 20 upon which the arms 11 rest when in their normal or working position.

It will be understood that the retainer is of such solidity or strength that the collar 10 3 of the drill steel may be permitted to strike against the retainer and set up sufficient vibration in the steel to loosen it from any bad hole wherein it would otherwise remain stuck. Moreover the retainer 15 is so mounted that it may readily yield with respect to the front head of the drill by reason of the provision of the spring 5.

I prefer to make the retainer proper out 20 of a piece of flat stock in the manner shown, thereby providing great strength with comparatively little weight. Moreover the sliding ring or collar 14 which surrounds the arms of the retainer proper is adapted to act as a support preventing the retainer from 25 spreading or becoming distorted in any way due to strain put upon it. This collar also affords quick and simple means for holding the retainer in position.

I claim:—

30 1. In combination with the front head of a machine and its projecting working tool, a tool retainer comprising a collar on the head, a retainer proper having side arms pivoted on the collar and having a central

35 portion adapted to cooperate with the working tool, and means for holding the retainer in such cooperating position, consisting of a collar surrounding and movable longitudinally of said arms.

40 2. In combination with the front head of a machine and its projecting working tool, a tool retainer comprising a collar on the head, a retainer proper having side arms pivoted on the collar and having a central

45 portion adapted to cooperate with the working tool, and means for holding the retainer in such cooperating position, consisting of a collar surrounding and movable longitudinally of said arms, and a clutch 50 device for holding the latter collar in its forward or working position.

55 3. In combination with the front head of a machine and its projecting working tool, a tool retainer comprising a collar on the head, a retainer proper having side arms pivoted on the collar and having a central portion adapted to cooperate with the working tool, and means for holding the retainer in such cooperating position, consisting of 60 a collar surrounding and movable longitudinally of said arms, a third collar on the extreme front end of the head, and a catch device mounted on such third collar for holding the second mentioned collar in its forward or working position.

4. In combination with the front head of a machine and its projecting working tool, a tool retainer comprising a collar on the head, a retainer proper having side arms pivoted on the collar and having a central 70 portion adapted to cooperate with the working tool, and means for holding the retainer in such cooperating position, consisting of a collar surrounding said arms and having internal side recesses which receive such 75 arms and by which such collar slides thereon.

5. In combination with the front head of a machine and its projecting working tool, a tool retainer comprising a collar 80 mounted to yieldingly slide longitudinally on such head, the front head having spaced lugs at its extreme forward end, a collar having complementary grooves and recesses 85 to cooperate with said lugs whereby that collar is removably locked to the head, a spring between the two collars, and a member pivoted to the first mentioned collar and arranged to engage a tool.

6. The combination with the front head 90 of a machine and its projecting tool, of a tool retainer comprising a pair of collars and an intermediate spring all sleeved over said head, one collar and the head having cooperating surfaces to prevent relative 95 rotation between the same and to provide an abutment on the head against which the said collar abuts, and a tool-engaging member mounted on the said collar.

7. The combination with the front head 100 of a machine and its projecting tool, of a tool retainer comprising a pair of collars and an intermediate spring, all sleeved over said head, an abutment on said head 105 arranged to be engaged by one of said collars, a tool engaging member pivoted on said collar, and means operable upon the partial rotation of the other collar on said head for locking said last named collar on said head.

110 8. The combination with the front head of a machine and its projecting working tool, of a tool retainer comprising a pair of collars and an intermediate spring, all 115 sleeved over said head, an abutment on said head arranged to be engaged by one of said collars, a tool engaging member pivoted on last named collar, and a lug on said head, the other of said collars being slotted to pass over said lug and having a recess in 120 its outer face angularly removed from said slot for locking engagement with said lug.

9. The combination with the front head of a machine and its projecting working tool, 125 of a tool retainer comprising an assembly sleeved over said head from the end thereof and including a pair of collars, an intermediate spring and a tool engaging member pivotally attached to one of said collars, the other collar being provided with a slot and 130

a recess in its outer face angularly removed from said slot, and a lug on said head adapted to pass through said slot and to engage said recess upon a partial rotation of said last named collar to lock the same to the head.

10. In combination with the front head of a machine and its projecting working tool, a tool retainer comprising a collar

mounted to slide longitudinally on such head, said collar and head having cooperating portions to prevent rotation of the collar, a spring cooperating with said collar, and a retainer proper pivoted on said collar and having side arms and a central cross-portion, and stops adapted to be engaged by the side arms of the retainer.

CLARENCE H. DOCKHAM.
